Andrew Turner, of Reading, State of Connecticut.

Letters Patent.

The subscriber refers to in these Letters Patent and making part of the same containing a description in the words of the said subscriber turning himself of his improvement in the machine for boring stone for blasting

To all to whom these presents shall come,

Be it known that I, A. Andrew Turner, of Reading in the County of Springfield and State of Connecticut, have invented and applied to use a new and useful improvement in Machine for boring rocks or stone for blasting, called Andrew Turner's improved stone auger, and that the following with the annexed drawings is a full and accurate description thereof.

This invention consists of a shank C in Fig 1. upon the annexed drawing, to be of a length and diameter corresponding with the size and depth of the hole to be bored. To this shank is attached a chisel 23 fitted with a socket and joint, and fastened with a screw at D, at convenient and variable distance from the upper end of the shank is a swivel D, fitted so as to revolve around the shank, extending to E, having a joint at E and a handle at F, a post is fixed at F to support a small pulley I, a cord E' of sufficient size to work the chisel, passing through this pulley to which it is made fast, over the pulley, through the swivel near the shank and a small staple J, to the chisel, to which it is fastened by a pin. The hole in the rock to be blasted is to be bored to nearly the required depth in the ordinary way. Then the stone auger should be introduced into the hole thus bored, having a chisel attached to it, somewhat less than the hole, and the force is to be applied to the chisel by striking on the top of the shank, with a sledge, or hammer, or by elevating and forcing it down. The operator, by elevating and depressing the handle, by means of the cord E and the swivel D rocks the chisel, by means of the joint at D, and thus enlarges the chamber.

at the bottom of the hole, for the reception of the charge to any required dimension. A set of chisels, figures 2. A. of different lengths and sizes and having edges of different degrees of obliquity to the shank should be prepared, and in readiness so that the size of the chamber for the reception of the charge may be graduated and inequalities in the bottom of it, to a greater extent, cut off. A chisel, if necessary, a double set of chisels, Figures 3. & 4. B. & C. may be fitted in with cords, attached thereto in the same manner as has been already described in this case of the chisel B, these cords to pass up on both sides of the shank over the pulley and to be fastened to the handle, so that by elevating and depressing the handle, the two chisels will be made to strike in opposite directions, and thus cut faster and smoother than with a single one. As the chisel may fasten to the shank having a joint but without a screw, as in Figure 4. When the work with these chisels is completed, the bottom of the chamber will still be uneven. See a auger E Figure 5 with a spring G, may then be introduced — The shanks of this auger should be so bent near the bottom, and the edge of the chisel so arranged, that the chisel, when introduced upside, upon being turned, cut that part of the chamber which could not be reached by a common stone auger. The spring should be on the opposite side of the shank to the sharpest angle of the chisel, and extend downwards, so that the part G will hold the chisel to its place, and extend the extreme point of the chisel into the chamber. The dust is removed from the chamber by a scraper F Figure 6, consisting of a ~~slight~~ rod with a spoon C, of a suitable size, attached to the lower end, with a joint H, and cord E fastened to the spoon, and passing through a staple at K.

After the scraper is introduced into the chamber the operator by pulling the cord and moving the rod, can reach and clean every part of the chamber —

When there is water in the hole the charge is introduced in the following manner — A sack is prepared of leather, india rubber, or any other suitable material, impervious to water, corresponding in shape with the size of the hole, and the chamber, Figure 8 so that the bottom of the sack when filled with powder, will fill the chamber — In this sack is inserted a tin, or other thin metallic tube extending downwards to the point where the sack being enlarged. This sack and tube are then introduced into the hole and charged

stronged with founders. The blades and shanks should be of iron and cast
What I claim as my ^{new} invention and not previously known, in the above described
machine is the connecting of said blades to the shanks with a joint, and the mode
of working them, enlarging the bottom of the chamber, so that a much larger
charge may be introduced, and the force and effect of the charge, greatly
increased, and the mode of constructing and working the auger with a spring
also the constructing of the scraper with a spear, fitted to the end with
a joint. In testimony that the above is a true specification of
my said improvement as above described, I have hereunto set my hand this
twentieth eighth day of December in the year of our Lord one thousand
eight-hundred-and-thirty-six.
